United States Patent Office

Des. 217,217
Patented Apr. 21, 1970

217,217

SHOE OR SIMILAR ARTICLE

David Evins, New York County, N.Y., assignor to Evins
Incorporated, New York, N.Y.

Filed Aug. 18, 1969, Ser. No. 18,723

Term of patent 7 years

Int. Cl. D2—04

U.S. Cl. D2—290

FIG. 4

FIG. 1 is a perspective view of a shoe or similar article, showing my new design.

FIG. 2 is a side view thereof.

FIG. 3 is the opposite side of FIGURE 2.

FIG. 4 is a bottom view thereof.

I claim:

The ornamental design for a shoe or similar article, substantially as shown.
